UNITED STATES PATENT OFFICE.

ALLISON A. CLOKEY, OF RUTHERFORD, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed November 2, 1922. Serial No. 598,539.

This invention relates to telegraphy, and particularly to a method and system of high speed telegraphy adapted for use with long submarine cables.

It is an object of the invention to provide a high speed telegraph system capable of two way transmission for use under conditions where it is impossible to employ the ordinary duplex method of operation, in which it is necessary to maintain a very accurate balance.

Another object of the invention is to provide suitable switching apparatus at the terminals of a long submarine cable to automatically and alternately associate the transmitters and receivers at the terminal stations with the cable conductors, in such a manner as to provide the practical equivalent of simultaneous operation in both directions and still permit operation of the system at maximum efficiency.

In my copending application Serial No. 592,010, filed October 3, 1922, there is disclosed a somewhat similar telegraph system designed to accomplish practically the same objects. The present invention, however, relates to an improvement over the previous system in that it makes possible the operation of a telegraph system over a long submarine cable at its maximum efficiency by operating the terminal apparatus at the highest speed permitted by the characteristics of the cable.

Ordinary submarine cables are not adapted to high speed signaling because of distortion of the signaling impulses due to the large distributed capacity of the cable conductors. In view of the many difficulties to be overcome, it has not been the practice to inductively load such cables to overcome the effect of the large distributed capacity. However, by the use of a certain nickel iron alloy, which has appropriately been termed "permalloy," when properly prepared and made into a ribbon of proper proportions and laid spirally upon the cable conductor in the proper way, it is possible to transmit legible signals over a long submarine cable at very much greater speed than has been possible heretofore. However, when transmitting signaling impulses at the speed permissible with such a cable, difficulty arises due to inability to obtain or maintain a sufficiently accurate balance to permit duplex operation.

In an application of John J. Gilbert, filed May 15, 1922, Serial No. 561,138, there is described a method of two way operation which does not depend upon the conjugate relationship of transmitter and receiver as does the ordinary duplex method of operation. The present invention utilizes the same fundamental principle of operation as the Gilbert system in which the signaling impulses are transmitted over a loaded submarine cable at relatively low velocity so that an appreciable period of time, for example, a few tenths of a second, elapses between the time when the transmitting key is closed and the time of arrival of the transmitted impulse at the receiver of the distant station.

In accordance with a feature of the present invention, suitable mechanisms are provided for simultaneously and alternately associating the transmitters and the receivers at the terminal stations with the cable conductor for very short intervals of time which bear a definite relation to the time required to propagate a single impulse over the cable. In accordance with another feature of the invention means is provided for preventing the overlap of receiving and transmitting impulses, such means also being utilized for curbing the transmitted impulses.

These and other features of the invention will be more clearly understood by reference to the accompanying drawing in which Fig. 1 shows the preferred form of apparatus at one station of a high speed two-way telegraph system adapted for two-channel sending and receiving of signals. Fig. 2 shows corresponding segmented rings of the distributors located at the opposite ends of a cable and Fig. 3, corresponding to Fig. 1, shows the preferred arrangement of apparatus at the distant end of the cable.

Referring now to the drawing there is disclosed a telegraph system consisting of terminal stations A and B joined by the cable C. Each terminal station is provided with a special rotary distributor, these distributors being arranged to rotate in synchronism in accordance with means well known in the art. Each distributor comprises a transmitting section for transmitting impulses from a transmitting mechanism to the cable, a receiving section for receiving signals and transferring them to recording or printing mechanisms, a switch-

ing section for alternately connecting the transmitting and receiving sections with the cable, and a control section which controls the operation of the transmitting and receiving mechanisms in proper sequence. In the arrangement as illustrated two channels are provided for the transmission and the reception of impulses. The number of channels to be employed for efficient operation depends upon the maximum speed obtainable with the printing and transmitting mechanisms since it is desirable to operate the cable at its maximum efficiency.

At terminal station A, shown on Fig. 1 of the drawing, the transmitting segments 1 to 5 are shown connected in the usual manner to a transmitting mechanism 21. Transmitting segments 6 to 10 are connected in a similar manner to a second transmitting mechanism 22. Receiving segments 11 to 15 are connected to a printing mechanism 23 and receiving segments 16 to 20 are connected to a similar printing mechanism 24. A brush member 30 mounted on a rotatable brush arm 31 is adapted to successively engage segments 1 to 10 and connect them with a transmitting ring T, which in turn is connected through the winding of a curbing relay 25 and condenser 26 to a corresponding series of segments 40 to 49. The segments 40 to 49 are of the same length as segments 1 to 10 and are in alignment therewith on the distributor.

By means of a second brush member 32 mounted on the brush arm 31, the receiving segments 18 to 20 and 11 to 17 are connected successively to a solid ring section R which is connected to the armature of the line relay 35, which in its operated position is connected to a grounded source of energy 36. The winding of relay 35 is connected through a shaping network 37 to receiving segments 50 to 59 on the switching section of the distributor. These segments correspond in length and position to the receiving segments 18 to 20 and 11 to 17. Positioned between the transmitting and receiving segments of the switching section are the curbing segments 60-60 which are connected through the curbing condenser 61 to the armature of curbing relay 25. By means of the brush member 33, the transmitting segments 40 to 49, receiving segments 50 to 59 and the curbing segments 60-60 are connected with the ring member S which is connected to the cable C through a lengthening network 62, the purpose of which will be explained hereinafter.

The fourth section of the distributor comprises a solid ring member L which is connected to a grounded source of energy 63 and active segments 64, 65, 66 and 67. Segment 64 is connected to the tape advancing electromagnet 68 of transmitter 22; segment 65 is connected to the operating mag-

net 69 of printing mechanism 24; segment 66 is connected to the tape advancing electromagnet 70 of transmitter 21; and segment 67 is connected to the operating magnet 71 of printing mechanism 23. A brush member 34 also mounted on the rotatable brush arm 31 serves to connect local segments 64 to 67 with the ring L in proper order to cause the operation of the printing and transmitting mechanisms in the correct sequence.

With station B equipped in a similar manner to station A and assuming the brush arms to be driven in synchronism so that the brushes advance at a uniform speed over the developed distributor sections, the operation of the system is believed to be at once apparent. As brush 30 connects segment 1 to transmitting ring T an impulse is transmitted from the transmitter 21 through segment 1, brush 30, ring T, the winding of curbing relay 25, transmitting condenser 26 to transmitting segment 40 of the switching section. Since brush 33 advances uniformly with brush 30 the circuit is extended from segment 40 through brush 33, ring S, and lengthening network 62 to cable C.

Due to the characteristics of the cable, appreciable time elapses before the signal propagated at station A arrives at station B. In the present case, as will be seen by referring to Fig. 2, it has been assumed that this period of time will be such that the brushes have advanced to the point X-X and are just engaging with receiving segments 11-11'. The impulse therefore transmitted from segment 1 at station A upon reaching station B passes through the lengthening network 62' to ring member S' of the switching section, is transmitted through brush member 33' to segment 53' and thence through the shaping network 37' and relay 35' to ground. The operation of relay 35' causes the impulse to be transmitted from the grounded source of energy 36' through the armature of relay 35' to ring R', thence through brush 32' to receiving segment 11' which is connected to the printing mechanism 23'. In a similar manner, due to brush 30 at station A wiping over transmitting segments 2, 3, 4 and 5 impulses are received at station B on segments 12', 13', 14' and 15' and operate the respective electromagnets of printer 23' to set up the predetermined character. Upon further rotation of the brush arm carrying brush 33', the brush member 34' connects local segment 67' with the ring member L' thus completing a circuit from the grounded source of energy 63' through ring member L', brush 34', local segment 67' and operating magnet 71' to cause the operation of the printing mechanism.

During the interval that an impulse is being transmitted from segment 1, the wind-

ing of the curbing relay 25 is in series with the cable and its armature is therefore moved against the contact member which is opposite in polarity to that of the transmitted signal. As the transmission of that signal is completed, the brush 33 passes from segment 40 onto segment 60 and a short curbing impulse, opposite in polarity to that of the signal just transmitted, is applied to the cable due to the charging of the curbing condenser 61. This curbing impulse serves to correct the wave form of the transmitted signal in a manner well understood in the art.

15 As the brush 33 passes onto segment 50 simultaneously with the brush 32 passing upon receiving segment 18, the cable C is connected through lengthening network 62, ring S, brush 33, segment 50, shaping network 37 and relay 35 to ground. This connection is made at the exact instant that a current impulse transmitted from station B reaches station A and the relay 35 is therefore energized causing an amplified impulse 20 to be sent from the grounded source of energy 36, through the armature of relay 35, ring R, brush 32 to receiving segment 18 and thence to one of the electromagnets of the printing mechanism 24. The impulse received by the segment 18 is the third of a 25 series of five impulses transmitted from station B during a previous rotation of the distributor. Simultaneously with brush 30 engaging segment 1, brush 34 joins local segment 64 with the ring member L thus completing a local operating circuit from the grounded source of energy 63 through ring L, brush 34, segment 64 and electromagnet 68 of the transmitter 22. The operation of 30 electromagnet 68 serves to step the tape ahead in preparation for a subsequent transmission of a series of impulses. As brush 30 advances uniformly over segments 2 to 10, impulses are transmitted by transmitter 21 in a manner similar to that already described for one channel and then by transmitter 22 for the second channel. Alternately with the transmission of impulses, the 35 cable is connected to the receiving segments 18 to 20 and 11 to 17 in order.

Immediately after an impulse has been received on receiving segment 20 the brush member 34 engages local contact 65 thereby completing a circuit from the grounded source of energy 63, ring member L, brush member 34, segment 65 to operate magnet 69, the operation of which causes the printing 40 of the character as set up on printing mechanism 24. In a similar manner as brush 30 engages transmitting segment 6, brush member 34 connects local segment 66 with ring member L thus causing the energization of electromagnet 70 which steps ahead the tape of transmitter 21.

45 The number of channels to be employed in

a particular installation depends largely upon the speed of transmission of the cable and the speed of operation of the terminal apparatus, it being advisable to increase the number of channels to a point approaching 50 that at which the cable is operated at its maximum permissible speed. Since there must be exact relationship between the speed of transmission and the time interval required by a current impulse to traverse the 55 cable, it follows that the time required for a current impulse to traverse the cable must be equal to that taken by the brushes of the distributor in wiping over a certain number of transmitting segments. In the system 60 illustrated it is assumed that the time of transmitting an impulse over the cable conductor is equal to the time required for the brushes to wipe over four transmitting segments. Thus, at station A the brush, after 65 transmitting a signal from segment 1 passes over the subsequent transmitting segments 2, 3, and 4 and is just passing upon receiving segment 11 when the transmitted impulse is received at station B on segment 11'. 70

It will be noted that this system can be operated at its maximum possible speed less a fraction of the time required by the distributor brush in passing over a single pair of transmitting and receiving segments, instead of being delayed by a fraction of the time required for the brushes to pass over a series of five impulses which determines the character to be printed. Only very rarely will the time of signal propagation be 75 exactly equal to the time required by the brushes to traverse the required distance on the distributor, and, as it would be undesirable to alter either the speed of transmission or the length of the distributor segments, the lengthening network 62 is provided to lengthen the time of propagation. The additional time lag thus introduced will never exceed the time required by the 80 brushes to travel the distance between the 85 successive receiving segments. 90

95 What is claimed is:

1. In a telegraph system a cable and a pair of terminal stations connected to the ends thereof, each of said terminal stations comprising a transmitting mechanism, a receiving mechanism and switching means for associating either the transmitting mechanism or the receiving mechanism alternately with the cable after the transmission or reception of each signal impulse over said cable. 100

105 2. In a telegraph system a cable and a pair of terminal stations connected to the ends thereof, each of said terminal stations comprising a transmitting mechanism, a receiving mechanism and switching means to associate either the transmitting or the receiving mechanism alternately with the 110 cable after the transmission or reception of 115 120 125 130

each current impulse at that terminal, said switching means being driven in synchronism and arranged to provide simultaneous transmission and simultaneous reception at the terminal stations.

3. In a telegraph system a cable and a pair of terminal stations connected to the ends thereof, each of said terminal stations including a transmitting mechanism, a receiving mechanism and a rotary distributor, said distributors being driven in synchronism and each including a transmitting section, a receiving section, a switching section for alternately connecting said transmitting and receiving sections to the cable after the transmission or reception of each signal impulse over the cable, and a control section for controlling the operation of the receiving and transmitting mechanisms.

4. In a telegraph system a cable, and a pair of terminal stations connected to the ends thereof, each of said terminal stations including a transmitting mechanism, a receiving mechanism and a rotary distributor, said distributors being driven in synchronism and each including a transmitting section, a receiving section, and a combined switching and curbing section for alternately connecting the transmitting and receiving sections with the cable and for curbing the impulses transmitted over the line.

5. In a telegraph system a loaded cable, and a pair of terminal stations connected to the ends thereof, each of said terminal stations including a transmitting mechanism, a receiving mechanism and a rotary distributor, said distributors being driven in synchronism and each including a transmitting section, a receiving section, and a switching section for alternately associating the transmitter and receiver of that terminal with the cable after the transmission or reception of each signal impulse over the cable and for periods of time bearing an exact relationship with the time required for a signal transmitted from one station to arrive at the receiver of the other station.

6. In a telegraph system a loaded cable, and a pair of terminal stations connected to the ends thereof, each of said terminal stations comprising a transmitting mechanism, a receiving mechanism, and switching means for alternately associating the transmitting mechanism and the receiving mechanism with the cable, the time represented by a plurality of successive transmitting and receiving periods being equal to the time required for a signal impulse transmitted from one station to arrive at the receiver of the other station.

7. In a telegraph system a cable and a pair of terminal stations connected to the ends thereof, each of said terminal stations comprising a transmitting mechanism, a receiving mechanism, and automatic means for

associating either the transmitting mechanism or the receiving mechanism alternately with the cable after the transmission or reception of each impulse over the cable.

8. In a telegraph system a cable, a lengthening network connected thereto, and a pair of terminal stations connected to the ends of the cable, each of said terminal stations comprising a transmitting mechanism, a receiving mechanism, and switching means for alternately associating the transmitting mechanism and the receiving mechanism with the cable, the time represented by a plurality of alternate transmitting and receiving periods being equal to the time required for a single impulse to travel over the cable and the lengthening network.

9. A method of two-way signaling between two stations which consists in alternately simultaneously transmitting and simultaneously receiving at both stations, said change from transmitting to receiving, or vice versa, taking place after the transmission or reception of each signal impulse.

10. A method of two-way signaling between two stations which consists in both stations simultaneously transmitting and receiving alternate signal impulses over a cable at a frequency having a definite relation to the time of propagation of a current impulse over the cable.

11. A method of two-way signaling between two stations which consists in both stations simultaneously transmitting an impulse over the cable, sending out a curbing impulse, and then receiving a current impulse, the period of alternately transmitting and receiving a group of current impulses being equal to the time of propagation of a current impulse over the cable.

12. A method of two-way signaling over a conductor which has an appreciable propagation period and is provided with means for operatively associating it with both transmitters simultaneously and disassociating it from them and for operatively associating said conductor with both receivers, which method comprises operating said means to associate the transmitters with the cable to transmit a single impulse, disassociating said transmitters from the cable and transmitting a curbing impulse thereover, associating the receivers with the cable to receive a single impulse and then disassociating the receivers from the cable, the speed of operation of said means being such that the time required for a plurality of transmitting, curbing and receiving periods is equal to that time of propagation of a single impulse over the cable.

In witness whereof, I hereunto subscribe my name this 31st day of October A. D., 1922.

ALLISON A. CLOKEY.
